UNITED STATES PATENT OFFICE.

ROBERT A. BROOKS, OF CHICAGO, ILLINOIS.

APPARATUS FOR FLUSHING WATER-CLOSETS.

1,265,601.

Specification of Letters Patent.

Patented May 7, 1918.

Application filed June 29, 1917. Serial No. 177,818.

To all whom it may concern:

Be it known that I, ROBERT A. BROOKS, a citizen of the United States, residing at Chicago, in the county of Cook and State of Illinois, have invented certain new and useful Improvements in Apparatus for Flushing Water-Closets, of which the following is a specification.

My invention relates to means for flushing a series or battery of water closets, and is particularly applicable to situations in which the pressure of water in the service pipe is relatively high. One object of my invention is to so organize and coördinate the parts of the apparatus as to entirely dispense with individual tanks in the different closets for measuring a charge of water which is emptied to accomplish a flush, the water, for this purpose being supplied by a direct flow through a supply valve in the master tank and distributed as needed to the various flushing devices. Another object is to provide a cheap, efficient and durable flushing device operating through siphonic action and eliminating all accurately fitted valves in the entire system excepting a single ball or float valve in a master tank, and in fact eliminating the necessity for accurate fitting of this valve also, since even in case of considerable leakage past the valve the surplus water will escape through the closets without any flushing operation taking place. An overflow pipe in the master tank is for this reason not required. Inasmuch as there are no accurately fitted parts, valves, washers, packed stems, etc., in my system, practically no repairs are needed, and the system once installed will remain in perfect working order with a minimum of attention, and under conditions, such as a highly mineralized or dirty water supply, where ordinary systems would need frequent repairs. With the foregoing and incidental objects and advantages in view I have devised the apparatus shown in the accompanying drawings and in which my invention is embodied, the essential elements thereof being more particularly pointed out in the appended claims.

Of the drawings, Figure 1 is a vertical section through the master tank and connected supply pipe and flushing device of one of the closets of the system; Fig. 2 is a front elevation showing somewhat dia-

grammatically the arrangement of the master tank and individual flushing devices in several adjacent closets; Fig. 3 is a fragmental vertical section showing a modified form of the parts by which the siphonic flushing action is initiated; and Fig. 4, a vertical section of a different form of flushing device.

The same reference characters indicate the same parts in all the figures of the drawing.

The master tank 1 of a battery of water closets A, B, C, D, etc., to which my invention is applied is supported in any convenient or suitable manner at the height at which overhead tanks having siphon flushing valves are usually arranged, say about seven feet from the floor. Water from the service main 2 is admitted through a ball-cock valve 3 of ordinary construction, but which should be of large capacity, controlled by a float 4 at the end of a lever 5 operatively connected with the valve. A supply pipe 6 of large capacity leads from the lower part of the master tank horizontally through or adjacent the rear of the closets, and is connected with a flushing device individual to each closet.

In the present instance the flushing devices are each supported by a T-union 7 interposed in the line of the supply pipe 6, and the operative parts of each device are inclosed in a cylindrical shell 8 provided at its lower end with a threaded neck engaging the stem of the union. Some distance below its top the shell 8 is formed with a cross partition 9 separating a piston chamber in the lower part of the shell from a timing chamber at the top and having a central opening forming a bearing for the stem 10 of a piston 11. The piston comprises a head 12 upon which rests a loose-fitting disk 13 formed with an annular imperforate marginal portion and above the head 12 openings leaving a connected central spider slidingly engaging the piston stem. The partition 9 of the casing is formed with a series of openings 9^a around the central bearing for the stem of the piston, and above the partition there is arranged a disk 14 loosely fitting upon the stem and at one side equipped with a regulating screw 15 by which any desired degree of leakage downwardly past the disk may

be attained. The upper end of the piston stem is operatively engaged by one end of a pivoted lever 16, the other end of such lever being arranged to be actuated by a 5 chain or rod 16^a operated by a handle pull in the usual manner.

Immediately below the cross partition 9 of the casing the top of the piston chamber therein communicates through a quarter- 10 turn pipe connection 17 with a flushing pipe 18 which forms the longer leg of the siphon for flushing the closet bowl to which it leads. It will be understood that the entire 15 system of inter-communicating flushing devices and master tank is arranged so that when the inlet valve 3 is shut off by the float 4 the water level in all the tanks will stand just below the pipe connection 17 just mentioned in each device.

20 A refilling device is interposed in the flushing pipe near its lower end, such device consisting of a closed casing 19 into which the upper section of the flushing pipe 18 opens, and into which the lower section 18^a 25 of the pipe extends upwardly to near the top, a restricted leak port 20 being formed in such lower section just above the bottom of the casing.

The operation of the device is readily 30 apparent from the foregoing description. The proportions of the piston chamber and flushing pipe and the size of the openings 9^a of the cross partition are such that upon forcible actuation of the operating connections the 35 piston will discharge a volume of water into the flushing pipe sufficient to start siphonic action, and also force a considerable volume of water into the timing chamber above the partition, the disk 14 lifting to permit this 40 action and then dropping until the regulating screw 15 contacts the partition. The reduction of pressure in the short leg of the siphon, that is, the piston chamber, draws water from the supply pipe 6 (which it will 45 be remembered is of large capacity so as to permit an unrestricted, free flow) and as the water level in the system and therefore in the master tank falls, the float 4 operates to permit the water at high pressure through 50 the large supply valve 3, with the result that the water flowing through the flushing pipe 3 is practically all supplied by direct flow through the supply valve. When the lever is released and the piston stem allowed to drop, 55 after siphonic action has been established, the strength of the current will hold the disk 13 elevated and permit the water to flow around it. This action continues until the water in the timing chamber has all 60 drained back past the disk 14 and through the openings 9^a, when the access of air will relieve the exhaustion and break the siphon. By adjustment of the regulating screw 15 the passage of water past the disk can be so 65 regulated as to lengthen or shorten the

period of siphonic action. Since the supply of water does not depend upon the refilling of individual tanks, one flushing operation can succeed another immediately as many times as desired.

70 So long as the siphonic action continues the casing 19 of the refilling device will be filled with water and the flow will pass directly through it. Upon cessation of the flush the water remaining therein below the 75 top of the lower section 18^a of the pipe will drain gently through the leak port 20 to refill the closet bowl.

In Fig. 3 I have shown a simplified form 80 of piston in which the relatively small piston head 12 and loose-fitting disk 13 are replaced by a piston head 21 secured rigidly to the stem 10. In this case the parts are so proportioned that the space around the piston will be just sufficient to permit the flow 85 of enough water to fill the discharge pipe 18, but not so large as to permit a considerable proportion of the water above the piston to pass by it to the lower side when the piston is lifted. For instance, if the discharge pipe 90 is one and one-fourth inches in diameter, and the shell four inches, the area of the former will be 1.227 square inches, and the area of the latter 12.56 square inches or more 95 than eleven square inches in excess of the discharge pipe. Assuming the lever to have a lift of two and a half inches the cubic contents of the space in the chamber traversed by the piston would be about twenty eight cubic inches, and deducting say four 100 cubic inches as the amount which would pass below a piston properly proportioned, the piston would discharge into the flushing pipe and into the timing chamber a total volume of twenty four cubic inches of water, 105 or quite sufficient to start siphonic action and provide for regulating the length of flow.

110 While the novel forms of siphonic flushing devices above described are of great utility in connection with the organization of apparatus shown, it will be understood that in this general organization a different form of flushing device may be employed. In Fig. 4 I have illustrated such a modification 115 of my invention, in which the flushing device is supported by means of a four-way union 21^a interposed in the supply pipe 6, and includes a short stand pipe 22 rising to a point above the water level and upon which 120 is supported by suitable brackets a pivoted operating lever 23 engaging the stem 24 of a flushing valve 25. The closing movement of this valve is controlled by a retarding valve 26, which comprises a piston working in a closed cylinder 27 containing a body of oil or other suitable liquid, the piston head 28 being provided with an upwardly closing ball check 29 and also provided with a regulating screw 30 arranged to adjust the 125 130

size of an orifice through the valve head, and the piston stem 31 being connected to the stem of the flushing valve.

As in the apparatus first described, the 5 supply pipe 6^a is of ample capacity to carry a direct flow of water entering the master tank through the inlet valve, and passing from the tank through said supply pipe into and through the maximum number of flush- 10 ing pipes which are liable to be in operation at one time.

While my invention is particularly adapted for use in installations where the service pipe is under a relatively high pressure sup- 15 plying a large volume of water, I may adapt it for use in situations where the pressure is not so great by employing storage or supply tanks at such intervals as are needed to guard against the contingency of a greater 20 volume of water being required for the simultaneous flush of several closets than could be supplied through the inlet valve and master tank.

I claim:

25 1. Apparatus for flushing a battery of water closets comprising a service pipe supplying water at high pressure, a master tank, a float-controlled inlet valve of large capacity in said tank, a series of water containers ar- 30 ranged to contain water at the level of the master tank, a common supply pipe of large capacity in communication with said master tank and said containers, flushing pipes for the respective closets, and flushing devices 35 in said containers arranged when operated to initiate a flush of water which is immediately drawn directly from said inlet valve through said master tank and supply pipe.

2. Apparatus for flushing a battery of wa- 40 ter closets comprising a service pipe supply- ing water at high pressure, a master tank, a float-controlled inlet valve of large capacity in said tank, a vertical water container of small capacity in each closet arranged to 45 contain water at the level of the master tank, a common supply pipe of large capacity in communication with said master tank and said containers, flushing pipes for the re- spective closets, and flushing devices includ- 50 ing a reciprocable vertical stem in said con- tainer arranged when operated to initiate a flush of water which is immediately drawn directly from said inlet valve through said master tank and supply pipe.

55 3. Apparatus for flushing a battery of wa- ter closets comprising a service pipe, a master tank, a float-controlled inlet valve in said tank, a common supply pipe in com- munication with said master tank and ex- 60 tending through all the closets, a casing in- closing a piston chamber communicating with said supply pipe in each closet, said casing being arranged to contain water at the level of the master tank, a flushing pipe 65 connected above the water level with said

casing and constituting therewith a siphon, a piston in said chamber for expelling the water therein into the flushing pipe to start siphonic action, and means for interrupting the siphonic action.

4. Apparatus for flushing a battery of water closets comprising a service pipe, a master tank, a float-controlled inlet valve in said tank, a common supply pipe in communication with said master tank and ex- 70 tends through all the closets, a vertical cy- lindrical shell forming a piston chamber communicating at its bottom with said sup- 75 ply pipe in each closet, said chamber being arranged to contain water at the level of the master tank, a flushing pipe connected above the water level with said chamber and con- 80 stituting therewith a siphon, a piston in said chamber for lifting the water therein and expelling it into the flushing pipe to start 85 siphonic action, and means for interrupting the siphonic action.

5. Apparatus for flushing a battery of water closets comprising a service pipe, a master tank, a float-controlled inlet valve in 90 said tank, a common supply pipe in communication with said master tank and ex- tends through all the closets, a casing in- closing a piston chamber communicating with said supply pipe in each closet, said 95 casing being arranged to contain water at the level of the master tank, a flushing pipe connected above the water level with said casing and constituting therewith a siphon, a water chamber arranged above and com- 100 municating with the top of the siphon and having check means permitting a regulated upward flow of water into the chamber and a relatively restricted downward flow there- from, and a piston in said piston chamber 105 for expelling the water therein partly into said chamber and partly into said flushing pipe.

6. A flushing device for flushing water closets comprising a master tank, means for 110 maintaining a constant level therein, a ver- tically disposed casing formed with a perfo- rated cross-partition dividing it into a pis- ton chamber and a timing chamber and ar- ranged to contain water in the piston cham- 115 ber at the level of the master tank, a flush- ing pipe communicating with said piston chamber above the water level and constitut- ing therewith a siphon, and a piston in said piston chamber for expelling water into the 120 flushing pipe to start siphonic action and also expel water through the orifices in said partition into said timing chamber to tem- porarily seal the top of the siphon.

7. A flushing device according to claim 6 125 provided with means for retarding the re- turn of water from the upper to the lower side of said cross-partition.

8. A flushing device according to claim 6 130 provided with a loosely fitting disk arranged

- above the orifices in said partition and adapted to be lifted by water passing upwardly through them to permit relatively free passage.
5. 9. A flushing device for flushing water closets comprising a master tank, means for maintaining a constant level therein, a vertically disposed casing formed with a perforated cross-partition dividing it into a piston chamber and a timing chamber and arranged to contain water in the piston chamber at the level of the master tank, a flushing pipe communicating with said piston chamber above the water level and constituting therewith a siphon, a piston in said piston chamber and a piston stem connected thereto and extending upwardly through said cross-partition, and a loosely fitting disk surrounding said stem above said partition and arranged to cover the orifices therethrough.
10. A flushing device according to claim 9 in which the disk is equipped with a regulating screw for varying the return of water from above to below the partition.
11. A flushing device for flushing water closets comprising a master tank, means for maintaining a constant level therein, a vertically disposed casing formed with a perforated cross-partition dividing it into a piston chamber and a timing chamber and arranged to contain water in the piston chamber at the level of the master tank, check means controlling the passage of water through the orifices in said partition and permitting relatively free passage of water upwardly and a restricted return flow, a flushing pipe communicating with said piston chamber above the water level and constituting therewith a siphon, and a piston in said piston chamber, said piston comprising a stem and a relatively small head secured thereto and a plate slidably mounted on the stem above the head and perforated opposite such head.
12. A flushing device for flushing water closets comprising a master tank, means for maintaining a constant level therein, a vertically disposed casing formed with a perforated cross-partition dividing it into a piston chamber and a timing chamber and arranged to contain water in the piston chamber at the level of the master tank, check means controlling the passage of water through the orifices in said partition and permitting relatively free passage of water upwardly and a restricted return flow, a flushing pipe communicating with said piston chamber above the water level and constituting therewith a siphon, and a piston in said piston chamber, said piston being equipped with check means preventing displacement of water from above to below and permitting a free flow of water in the opposite direction.
13. In a siphonic flushing device, a timing device for interrupting the siphonic action comprising a water chamber arranged above the top of the siphon and having restricted communication therewith, and means for supplying said chamber with a charge of water to seal it from the air at the beginning of each flushing operation, the exhaustion of water from said chamber acting to admit air to the top of the siphon and interrupt the siphonic flow.
14. In a siphonic flushing device, a timing device for interrupting the siphonic action comprising a water chamber arranged above the top of the siphon and having communication therewith through a connecting orifice, a plate above said orifice permitting restricted passage of water therethrough, and means for supplying said chamber with a charge of water to seal it from the air at the beginning of each flushing operation, the exhaustion of water from said chamber acting to admit air to the top of the siphon and interrupt the siphonic flow.
15. In a siphonic flushing device, a timing device for interrupting the siphonic action comprising a water chamber arranged above the top of the siphon and having communication therewith through a connecting orifice, a movable plate over said orifice arranged to permit a relatively free movement of water from the siphon into said water chamber and a retarded flow in the return direction, and means for expelling water from the siphon into said chamber to seal it from the air at the beginning of each flushing operation, the exhaustion of water from said chamber acting to admit air to the top of the siphon and interrupt the siphonic flow.

ROBERT A. BROOKS.
